UNITED STATES PATENT OFFICE.

PHILANDER M. CURTIS, OF LEBANON, INDIANA.

SIDING GAGE AND SQUARE.

SPECIFICATION forming part of Letters Patent No. 396,075, dated January 15, 1889.

Application filed May 10, 1888. Serial No. 273,453. (No model.)

To all whom it may concern:

Be it known that I, PHILANDER M. CURTIS, of Lebanon, county of Boone, and State of Indiana, have invented certain new and useful 5 Improvements in Siding Gages and Squares; and I do hereby declare that the following is a full, clear, and exact description thereof, reference being had to the accompanying drawings, in which like letters refer to like 10 parts.

My invention relates to improvements in the construction of devices for gaging and squaring siding-boards, and will be understood from the following description.

15 In the drawings, Figure 1 is a back view of my device, one arm of the straight-edge being broken off. Fig. 2 is a side view of the device. Fig. 3 is an edge view of the straight-edge and the upper part of the arm to which 20 it is attached, also showing the upsets at each end. Fig. 4 is a front view of Fig. 1.

In detail the device consists of the gage *g*, having the projection *p*, the groove *gr*, formed in its inner face, and the spur *2*, near its upper end.

25 *a* is an arm hinged at 1 to the projection *p*, as shown in Figs. 1 and 2. The lower end of this arm is rounded, so as to permit it to be thrown forward when desired in the position 30 shown in Fig. 2.

g' is a gage-block, having a tongue, *t*, which moves in the groove of the gage *g*, and is secured to the gage by a set-screw, *sc*, passing through a squared block, *b*, which fits in a recess in the gage-block *g'*, and is connected with another slot, through which the set-screw passes into the gage *g*. This construction is 35 shown fully in Fig. 4 and in the dotted lines in Fig. 2. The gage-block *g'* is thus adjustable along the face of the gage *g*, and is set at any distance needed by the operator, according to the width of the siding used and the lap desired.

The lower siding-board having been nailed 45 in position upon the studding, my device is then set so that the upper end of the gage-block *g'* is brought directly beneath and against the under edge of the siding thus nailed on the studding. With a tap of the 50 hammer the spurs *2* and *3* are then driven into the siding firmly enough to hold the device in position without any further help. At

any desired distance from the gage thus set in position another one is secured in the same way to hold the other end of the next board. 55 This next board is then brought down, so that its under edge rests upon the top of the gage *g* just above the spur *2*. If it is necessary to cut this off, so as to true the ends, the arm *a* is then thrown forward against the board and 60 a line scribed down the right-hand side of this arm upon the board as a guide for sawing it off.

Usually one of the gages is set against the side of the corner-strip and another one some 65 distance off against one of the studding, and in practice it makes no difference whether the siding is to be cut off so as to fit against the corner-strip or to meet the adjoining end of the next siding-board in the middle of one of 70 the studding, as the inclination of the arm *a* is always that of the siding, and a line will be correctly drawn for cutting off the ends of the board, so that they always fit into place, needing no further preparation except, perhaps, 75 to trim off the edges with a block-plane. When this siding-board has been nailed in place against the studding, the gages are removed and reset, so that the upper end of the gage-block *g'* will rest beneath the lower edge of 80 the siding-board just nailed on, the spurs driven in again, and another board set in place on top of the gage *g*. The operator proceeds, board after board, resetting his gages with each successive board, the arm *a* being 85 always available, the device being held up by the spurs of the gage, so that the workman can rapidly mark the boards for cutting off wherever desired. No nails are necessary for holding the boards up, and no try-squares or 90 measuring-rules, for the gages enable the workman to dispense with all of these and save him a great deal of time and labor.

The straight-edge *s* is used as follows: When the siding needs to be cut off at an angle to 95 conform to that of the frieze-board in the gable, this straight-edge, moving on the central pivot, 4, can be turned so as to incline in either direction, as shown in Figs. 1 and 4. The upsets on the ends of the straight-edge 100 are intended to go under the lower edge of the frieze-board, so as to have two points of bearing, one at each end of the straight-edge; and the operator then draws along the straight

upper edge of this arm *s*, the line giving the angle at which to cut off the siding, so that it will fit against the inclined lower edge of the frieze-board. In ordinary work, as has been 5 said, the piece *s* is not used.

It will be seen that by means of this device the use of the try-square, dividers, and measuring-rules for gaging are entirely avoided. The operator can set his gage in the first in- 10 stance so that the width of the lap may be accurately marked off by the instrument itself, and the arm *a* takes the place of the try-square and always gives a true angle, conforming, as it always does, to the slope of the 15 weather-boarding upon the side, while the straight-edge *s* performs a similar service in determining the angle at which the siding is to be cut off to conform to the angle of the frieze-board in the gable.

20 I am aware that adjustable siding-gages provided with spurs for holding the same in position are not new, and do not broadly claim the same as my invention; but I am not aware

that any such adjustable gage provided with a hinged arm for squaring the side at the 25 point where it is cut off and carrying a pivoted straight-edge upon the upper end of such arm has ever been known or used.

What I claim as my invention, and desire to secure by Letters Patent, is the following, to 30 wit:

The siding-gage herein described, comprising the gage *g*, having the spur 2, the adjustable gage-block *g'*, connected therewith, having the spur 3 upon its face, and the movable 35 arm *a*, hinged to the gage *g*, as shown, and carrying the straight-edge *s*, pivoted at its upper extremity, all combined substantially as shown and described.

In witness whereof I have hereunto set my 40 hand this 28th day of April, 1888.

PHILANDER M. CURTIS.
